UNITED STATES PATENT OFFICE

2,448,050

TYPEWRITER PAGE END INDICATOR

Emmett A. Randolph, La Grange, Tex.

Application March 14, 1946, Serial No. 654,453

3 Claims. (Cl. 197—189)

1

The invention relates to a new typewriter page end indicator which will give a setting for any amount of margin at the bottom of paper being typed on and give an audible signal when the selected margin is reached. It affords more efficient typing, and banishes the guessing of margin or trouble of typing too close to bottom of paper. The bottom margin set is operated in connection with a small gear placed on the knob shaft of the platen and the setting is not effected by any amount of forward or backward turning of the platen within the complete typing area of the paper. The bottom margin set is designed to allow continued turning of the platen in either direction even after the setting or signal has been reached, and does not interfere with any movements of the typewriter.

One form of the invention is illustrated in the accompanying drawing in which

Figure 1 is a side elevational sectional view of the page end indicator attachment according to the present invention.

Figure 2 is an end elevational view, with parts broken away, of the indicator attachment shown in Figure 1.

Figure 3 is a fragmentary sectional view taken on the line 3—3 of Figure 2.

Figure 4 is a plan view of the trip piece.

Figure 5 is a plan view of the element or part carrying the bell clapper.

Figure 6 is an exploded view of the various elements comprising the indicator attachment according to the present invention.

The mounting plate 1 holds the bottom margin set mechanism. The bracket 2 which is attached to the mounting plate 1 is for mounting the assembly to the typewriter. The entire mechanism, with the exception of the bell and the clapper assembly, revolves in the bearing 32 in mounting plate 1. The large gear 6 turns with the shaft 8. Shaft 8 is held in the bearing 32 by the gear 6 and the flange 4 which is held to the end of shaft 8 with screw 5. The small gear 3 on the platen knob shaft of the typewriter meshes with and drives gear 6. All parts revolve on shaft 8 except the gear 6. Dial plate 7 is driven by the friction from the friction plate 16 against the gear 6. This friction is sufficient to turn the mechanism to trip the signal clapper, but not enough to interfere with the continued turning of gear 6 or the platen on the typewriter. Dial plate 7 and the setting plate 10 travel only between the two stops 33, 34 carried by the mounting plate. The nut 20 is adjusted to give sufficient pressure against the pressure plate 16, and

5 the nut 20 is locked by screw 21. When the setting mechanism dial plate 7 and setting plate 10 reaches either of stops 33, 34 the pressure is not great enough to apply any noticeable amount of friction on or against gear 6 thereby allowing continued turning of the platen on the typewriter, gear 3 and gear 6 with practically no added effort.

10 Dial plate 7 has attached to it the segmental flange 15 having graduations thereon, knob 35, and the index plate 9 as is shown in Figure 4. Plate 9 has many index holes for receiving pin 14 in setting for a desired margin at the bottom of the paper. The lever 40 is attached to the setting plate 10. The setting plate 10 has on it a tripping member or pin 12 in position to trip the bell clapper 26 in giving the signal that the desired margin is reached. On the lever 40 is the pointer 13 which is in position over the graduated segmental flange 15 of the dial plate 7. Washer 19 is placed between the nut 20 and the setting plate 10.

15 When setting, the paper is turned until there is about a 1½ inch top margin, and the setting for the bottom margin is then made by exerting a slight outward pressure against the knob 11 of the lever 40 and moving it to the desired point on the graduated flange 15. On the release of knob 11, the pin 14 enters a hole in the index 20 plate 9 which makes a permanent setting for the same amount of margin on the same size of paper. Immediately after this setting with knob 11 knob 35 is pushed back to stop 34. The machine is now ready to type and the signal will 25 sound when the selected bottom margin is reached. The knob 11 is not changed or pushed any more unless changing for a different margin or a different size paper. If not making any 30 change in the paper size or margin, the next sheet of paper is merely placed as before and the knob 35 is pushed back to stop 34 and the signal will sound as the same bottom margin is reached.

35 Pin 12 is in a position on plate 10 so that when the knobs 11 and 35 are on an even line with each other and as they are moved to stop 33 the bell will ring a little before the knobs 11 and 35 touch the stop 33. The setting of the pointer 13 is always between the knob 35 and the stop 33. 40 As shown in Figure 3, the bolt 24 is designed to hold the part 29 and the trip piece 28 with the nut 31 screwed down only enough to allow the part 29 and the trip piece 28 to move freely on the shaft of bolt 24. The bell clapper 26 is attached to the part 29 by the rod 30. A small

spring 27 is attached to the point 37 of the trip piece 28 and to the part 29 at the point where the clapper rod 30 is attached. The spring 27 allows the trip point 37 to be pushed back by pin 12 when it goes back to its starting position. The shoulder 36 on the trip piece 28, when the paper is nearing the bottom margin, catches 5 against the clapper piece 29 and raises clapper 26 up from the bell 22 until the pin 12 travels far enough to allow the point 37 to return to its original position, whereupon the bell clapper 26 falls on the bell 22 making a signal that the desired margin is reached. The bell 22 could 10 be of a different tone, or be replaced by a gong to distinguish the bottom margin signal from side or the regular margin bell. As shown in Figure 1, the hole 17 in the mounting plate 1 holds the bell bracket 23 and the bell 22, while the hole 18 in the mounting plate 1 holds the clapper 26 and the trip assembly. The spring 20 25 is mounted on the mounting plate 1 in position against the clapper rod 30 with enough pressure to keep the clapper 26 from resting on the bell 22.

I am aware that prior to my invention that there are combinations of gear and friction drives for other purposes. I therefore do not claim such a combination of a gear and friction drive broadly; but I claim:

1. In a page end indicator attachment for typewriters, a mounting plate, a graduated dial plate rotatably carried by said mounting plate, means carried by the mounting plate for operatively connecting the dial plate with the platen shaft of a typewriter for rotation in unison therewith, an index plate provided with a plurality of index holes attached to said dial plate and having its index holes arranged complementary to the graduations on said dial plate, a setting plate mounted for rotation with respect to the graduated dial plate and carrying a setting lever, said lever having a pointer cooperating with the graduations of the dial plate to indicate the setting of said setting plate, and also having a pin engageable in the hole of the index plate complementary to the graduation with which the pointer cooperates in any set position of the setting plate to lock the setting plate in set position with relation to the dial plate for rotation therewith, a signaling device carried by said mounting plate, and means on the setting plate for actuating the signaling device in response to rotation of the setting plate with the dial plate.

2. In a page end indicator attachment for typewriters, a mounting plate, a graduated dial plate rotatably carried by said mounting plate, means carried by the mounting plate for operatively connecting the dial plate with the platen shaft of a typewriter for rotation in unison therewith, an index plate provided with a plurality of index holes attached to said dial plate and

having its index holes arranged complementary to the graduations on said dial plate, a setting plate mounted for rotation with respect to the graduated dial plate and carrying a setting lever, said lever having a pointer cooperating with the graduations of the dial plate to indicate the setting of said setting plate, and also having a pin engageable in the hole of the index plate complementary to the graduation with which the pointer cooperates in any set position of the setting plate to lock the setting plate in set position with relation to the dial plate for rotation therewith, a tripping member on the setting plate, and a signaling device carried by said mounting plate and having a portion extending into the path of movement of the tripping member on the setting plate for actuation thereby.

3. In a page end indicator attachment for typewriters, a mounting plate, a rotatable shaft carried by said plate, a gear wheel fixedly carried by said shaft, gear means for driving said gear wheel from the platen shaft of the typewriter, a graduated dial plate loosely mounted on the said shaft, means for frictionally driving said dial plate from said gear wheel, an index plate provided with a plurality of index holes attached to said dial plate and having its index holes arranged complementary to the graduations on said dial plate, a setting plate loosely mounted on said shaft and carrying a setting lever, said lever having a pointer cooperating with the graduations of the dial plate to indicate the setting of said setting plate, and also having a pin engageable in the hole of the index plate complementary to the graduation with which the pointer cooperates in any set position of the setting plate to lock the setting plate in set position with relation to the dial plate for rotation therewith, stop means on the mounting plate for determining the initial position of the dial plate, a tripping member embodying a pin on the setting plate, and a signaling device carried by said mounting plate and having a portion extending into the path of movement of the pin of the tripping member on the setting plate for actuation thereby.

EMMETT A. RANDOLPH.
